DOORCHECK

Richard H. Wright, Cleveland Heights, Ohio

Application November 27, 1934, Serial No. 755,048

5 Claims. (Cl. 16—86)

The invention relates to doorchecks, and particularly to those types of doorchecks, which are especially applicable to doors for automobile or other vehicle bodies, and the like.

5 It is an object of the invention to provide a doorcheck which is simple and inexpensive, yet capable of withstanding and absorbing the shocks to which the same is subjected in checking and restricting the movement of the door.

10 A still further object of the invention is to provide a novel form of buffer, which may be applied to the doorcheck, so as to be always retained in position for absorbing the shocks incident to checking the door, as above referred to, in the most satisfactory manner.

15 The invention further contemplates the provision of a doorcheck buffer produced by extruding a suitable resilient material such as rubber.

20 Other and further objects and advantages of the invention will be hereinafter described, and the novel features thereof defined by the appended claims.

In the drawing:—

25 Figure 1 is a fragmentary horizontal sectional view taken on a plane substantially at the point of attachment of the doorcheck, the doorcheck being shown in plan.

Figure 2 is a fragmentary elevation presenting the parts of Figure 1 at substantially right angles to the view of Figure 1, a portion of the hinge post being broken away and shown in section.

Figure 3 is a plan view of the doorcheck without the buffer applied thereto.

30 Figure 4 is a side elevation of the doorcheck shown in Figure 3.

Figure 5 is an enlarged detail sectional view of one end of the doorcheck which carries the buffer, the buffer being shown mounted thereon.

Figure 6 is a view taken at right angles to Figure 5.

Figure 7 is an enlarged detail perspective view of the buffer.

Figure 8 shows a front elevation of a doorcheck looking in a direction as indicated in Figure 4 and illustrates a modified construction wherein the ends of the cross-head are flared outwardly.

Like characters designate corresponding parts in the several figures of the drawing.

Referring first to Figures 1 and 2, there is shown by way of illustration a door 1 mounted upon the vehicle body, generally designated 2, by a hinge 3, one leaf 4 of the hinge 3 being attached to the hinge edge 5 of the door and the other leaf 6 being suitably attached to the body

generally by means of a hinge post 7. The number of hinges applied to the door is immaterial, although there will generally be found at least two and frequently three.

It is customary to employ some form of doorcheck for limiting the extent to which the door may be opened. In the past, these have taken the form of leather straps, cables, plungers, etc. I have found that a simple and inexpensive doorcheck may be constructed in the form of a metal rod or bar 8 constituting a shank, one end of which is attached as by a bracket 9 to the hinge edge 5 of the door 1, the bracket, of course, being suitably secured to the door, as by a bolt 10 extending through the door frame. The rod or shank preferably pivots on the bracket at 11.

The opposite end of the rod or shank 8 extends through the hinge post 7, the latter being provided with a suitable aperture 12. This end of the shank carries at least one laterally extending arm, preferably two, forming a cross-head 13. The cross-head 13 may be formed integrally with the shank 8 or may be suitably attached thereto by welding or attaching devices such as rivets or bolts.

The cross-head which comprises oppositely extending arms is preferably U-shaped in form, and may extend either vertically or horizontally as desired according to the space which is available. As shown, the cross-head extends vertically.

The shank or rod 8 is curved so that in operation the check will be confined within the usual space afforded between the inner and outer walls of the vehicle body. The extent of the curvature 35 will vary with different makes of bodies, and it also depends on the arrangement of the hinge leaves.

The arms of the cross-head 13 are adapted to receive a buffer for the purpose of cushioning the 40 abutting engagement of the cross-head with the hinge post 7, the hinge post constituting the abutment against which the cross-head impinges when the door 1 is opened to the full limit permitted by the doorcheck.

As previously mentioned, the buffer according to my invention, is of novel construction, and preferably assumes the form of a resilient sleeve which may be slipped onto the cross-head arms so as to be retained thereon by the resiliency of the sleeve. In practice, it has been found desirable to thicken the sleeve at one side so as to provide an abutment engaging section of sufficient mass to satisfactorily cushion the shocks created in restricting the movement of the door 55

at its limit of travel in an opening direction. In the drawing, the sleeve is designated generally by the reference character 14, while the thickened section of the sleeve is designated 15.

5 Likewise, I have found, in practice, that it is desirable to provide some means for positively interlocking the buffer sleeve on its supporting arm so as to insure that the thickened section of the sleeve will remain in proper position to receive and absorb the shocks. Without such interlocking provisions, the sleeve has a tendency to turn on the arm eventually so that the shocks are received by the relatively thinner walls of the buffer, which, of course, do not have the capacity 10 for absorbing the same as does the thicker wall.

15 To produce this interlock between the buffer and the supporting arm, I provide an internally protuberant longitudinally extending rib 16, which is received in the channel 17 formed 20 by the side walls of the U-shaped arms of the cross-head 13.

25 I have found that a buffer sleeve having the construction above described, may be readily extruded in continuous form and cut in to sections of any desired length according to the length of the arm or arms carried by the doorcheck shank. Where two arms are provided at the end of the shank 8, a buffer unit is applied to each arm. The central openings through the buffer sleeve is 30 preferably slightly smaller than the supporting arms so as to provide a snug fit, the resiliency of the buffer serving to maintain the buffer on the arms without the additional provision for securing the same thereon.

35 The material from which the buffer is made is preferably rubber. Other suitable resilient compositions may, of course, be utilized.

40 In mounting the doorcheck, it may be located anywhere between the upper and lower extremities of the door, as desired. Likewise, if desired, more than one check can be provided per door. In practice, however, one per door will generally be found sufficient.

45 The operation of the invention should be readily apparent from the foregoing, and is briefly summarized as follows:—

50 Assuming the door to be at the limit of its open position as shown in Figures 1 and 2, upon closing the door, the shank 8 will slide through the aperture 12 to the left, (as observed in the drawing), pivoting about the point 11, as it does so, and keeping closely adjacent to the outer wall of the vehicle body so that in final closed position, the buffer supporting end of the shank will be 55 substantially spaced from the hinge position 2. Upon opening the door, the shank 8 will be withdrawn through the aperture 12 until the buffer strikes the inner face of the hinge post 7. The impact shock will be absorbed by the thickened 60 wall 15 of the buffer, which wall is located so as to extend towards the hinge post 7 for abutting thereagainst, being positively retained in such position by the interlocking of the rib 16 with the channel 17.

65 If desired, the cross-head 13 may be provided with lugs 13a so that when the sleeves have been arranged upon the cross-head, the lugs or locking means may be bent so as to maintain the sleeves in their proper position without likelihood of accidental removal. The cross-head 13 may also be a configuration as illustrated in

Figure 8, and the flared ends 13c will eliminate the possibility of accidental displacement of the rubber sleeves.

70 It will be obvious that the doorcheck described herein may be mounted in a reverse order with respect to the automobile body and door. In other words, the bracket 8 may be secured to hinge post 7, while the parts 2, 13 and 14, may be operatively arranged within the frame structure of the door 1.

75 While the specific details of construction have been herein shown and described, the invention is not confined thereto, as changes and alterations may be made without departing from the spirit thereof, according to the appended claims.

80 Having thus described my invention, what I claim as new and desire to secure by Letters Patent of the United States, is:—

1. A doorcheck of the class described, comprising a shank, one end of which is adapted to be 20 attached to the hinge edge of a door, and the other end of which carries at least one laterally extending arm adapted to coact with an abutment for limiting the movement of the door, and a buffer carried by said arm, said buffer comprising a resilient sleeve having a protuberance 25 extending therefrom and interlocking with said arm.

2. A doorcheck of the class described, comprising a shank, one end of which is adapted to be 30 attached to the hinge edge of a door and the other end of which carries a cross-head comprising oppositely extending arms of substantially U-form adapted to coact with an abutment for limiting the movement of the door, and a buffer mounted on said arms, said buffer comprising a resilient sleeve having an internal protuberant rib received within the channel formed by the U-shaped arms.

3. A doorcheck of the class described, comprising a shank, one end of which is adapted to be attached to the hinge edge of a door and the other end of which is provided with at least one laterally extending arm adapted to coact with an abutment for limiting the movement of the door, 45 and a buffer mounted on said arm, said buffer comprising a sleeve of resilient material slidable onto said arm and adapted to be maintained thereon by the resiliency of the sleeve, said sleeve being thickened at one side to constitute the 50 abutment engaging portion.

4. As a new article of manufacture, a buffer for doorchecks of the class described, comprising an extruded sleeve of resilient material, the wall of said sleeve being thickened at one side 55 to constitute an abutment engaging section and provided at the opposite side with an internally protuberant longitudinally extending interlocking rib.

5. A doorcheck of the class described, comprising a shank, one end of which is adapted to be attached to the hinge edge of a door, and the other end of which carries at least one laterally extending arm adapted to coact with an abutment for limiting the movement of the door, a 65 buffer carried by said arm, said buffer comprising a resilient sleeve having a protuberance extending therefrom and interlocking with said arm, and locking means on said arm for maintaining the buffer against displacement.
